METHOD OF IMPRESSING PLASTICS

Arthur M. Wickwire, Jr., Mountain Lakes, and
 John Muller, Waldwick, N. J., assignors to Peer-
 less Roll Leaf Co., Inc., Union City, N. J., a
 corporation of New York

Application February 11, 1939, Serial No. 255,905

3 Claims. (Cl. 41—37)

The invention relates to the method of impressing plastic material with stamping media.

Stamping media, including the heat releasable type, have been employed generally with success under commercial conditions for impressing and ornamenting materials of various character, but possessing the attribute of yielding under pressure of the stamping press. Such conventional practice has been carried out under the condition that the material stamped is at atmospheric temperatures. With heat releasable stamping pursuant to such conventional practice, the die is heated, usually by means of a controlled electrical resistance heating element, it being understood that the stamping medium is interposed between the face of the die and the material to be stamped.

It has long been desired to stamp plastics, but all efforts to obtain commercially satisfactory impressions within commercially acceptable proportion of spoilage following conventional practice, have failed. This has been due to many causes, a primary cause being that the facial area of a molded plastic due to inherent physical characteristics and imperfections unavoidable in the molding operation, is not uniplanar, but on the contrary is formed of irregular undulations of "hills" and "dales." The stamping medium, pursuant to conventional practice, if attached at all, is attached solely to the apices of the "hills," and wholly unattached at the "dales," and subject to ready dislodgement and otherwise commercially unacceptable. If it is sought to apply pressure greater than that of usual practice, in the effort to lodge the stamping medium in contact throughout with the surfaces of the "hills" and "dales," fracture or breakage of the plastic ensues, by reason of its brittleness.

We have discovered that when a molded mass of plastic material of the nature hereinbelow set forth, is preheated to a minimum predetermined temperature, the material of the face portion of the plastic desired to be stamped adapts itself to the contours of the design transmitting elements of the die by local displacement of the face material, and commercially satisfactory stamping is obtained attended by minimum spoilage. Further, particularly with heat releasable stamping medium, the face portion of the material of the plastic attains physico-chemical attributes effecting permanent retention of the outer sizing of the stamping medium.

Illustrations of suitable plastic material are: phenol-formaldehyde compounds, phenol-furfural compounds, urea-formaldehyde compounds,

vinyl chloride-acetate resins, methyl-methacrylate resins, styrene resins, shellac compounds, synthetic rubber compounds, cellulose compounds such as (a) ethyl cellulose, (b) cellulose acetate, (c) cellulose nitrate, casine compounds, synthetic alkyds, and modified oils, and the like.

Examination of the derived stamped product reveals that the stamped deposit makes a substantially continuous contact with the facial portion of the plastic, the local face portions of the material immediately adjacent the stamped deposit being ridged about the stamped deposit, thus defining a slight and surrounding the stamping with what might be described as a raised frame.

The above listed plastics, in current use, are characterized as molded at temperatures from approximately 225° F. upwardly, under compression molding pressures of from 1000 pounds per square inch and upwardly, and possessing the attribute of having substantially no tendency to cold flow, i. e., at atmospheric temperatures.

Further features and objects of the invention will be more fully understood from the following detail description and the accompanying drawing, in which—

Fig. 1 is a side elevation, largely diagrammatic, illustrating steps of a preferred procedure in carrying out the invention, with respect to a series of plastic articles;

Fig. 2 is a central vertical section, diagrammatically illustrating a die of a stamping press, a length of stamping medium and a section of a plastic article, the faces of which are exaggerated in undulating facial characteristics;

Fig. 3 is a view similar to that of Fig. 2, showing the die and therewith engaged stamping medium in pressure-engagement with a portion of an upper face of a plastic article; and

Fig. 4 is a vertical section of a plastic article succeeding the stage of stamping, pursuant to the hereinabove indicated procedure.

Referring to the drawing, 10 indicates an article of plastic material, of the nature hereinabove set forth. 11 indicates a suitable preheater referred to more fully hereinafter. 12 represents a suitable stamping press, the platen of which is indicated at 13.

Specifically, the stamping press is preferably 50 of the type set forth and claimed in the U. S. Patent No. 2,122,669, dated July 4, 1938, granted to Arthur M. Wickwire, Jr. An advantage attained by the stated Wickwire stamping press of particular value in carrying out the instant invention resides in the self-adjusting mounting of

the platen, i. e., upon mutually related spring-tensioned toggles, indicated at 14 whereby the platen accommodates itself to varying mean vertical dimensions of the article to be stamped, to present the mean plane of the face of the article to be stamped substantially at right angles to the face of the die 15 carried by the movable plunger 16, to which the die holder 17 is secured.

When practicing the invention under commercial conditions, a suitable conveyor indicated at 18 may be provided, for conveying the variant plastic articles 19, 19, etc. in seriatum through the preheater 11 to a position readily accessible to the operator of the stamping press 12.

A preheated article of any given plastic, designated 19a, in Figs. 1, 2, 3, and 4, upon having its temperature raised to its proper predetermined temperature, is shown in Fig. 1, in position upon the platen 13 of the stamping press. The stamping medium indicated at 19 is suitably fed to the face 19a of the die 15.

Preferably, the stamping medium 19 is of the heat releasable type, that is to say, embodying an inert carrier such as paper, or cellulose film of which the product known under the trademark "Cellophane" is a prominent illustration, or glassine paper or the like, upon one face of which is a layer of oleaginous heat releasable material, usually embodying beeswax, rosin or like resinous mixture; upon such oleaginous layer is applied gold film or leaf such as beaten gold, electrolytic gold or the like, or "imitation leaf" such as bronze powder for "imitation gold," aluminum powder for "imitation silver," etc. The stamping medium has an outermost layer of sizing, which may be shellac or the like, which may or may not have a pigment therein.

The assembly of a die 15, the heat releasable stamping medium 19 and the preheated plastic article 19a, at a stage immediately prior to the stamping operation, is diagrammatically illustrated in Fig. 2. As appears from Fig. 2, the upper face 19b of a molded plastic article is non-planar, the undulations being somewhat exaggerated, for the purpose of clarity of illustration. In the employment of a heat releasable stamping medium, the die holder 17 is heated by its heating element, not shown, pursuant to conventional practice employing a heated die assembly.

Figure 3 illustrates diagrammatically the stage of stamping, that is to say, the stage whereat the heated die 15 has brought the stamping medium 19 into contact with the undulated face 19b of the plastic article, and the impression face of the die and the interposed stamping medium into forceful impression contact with the face portion 19b of the plastic article 19a. Fig. 4 illustrates the impression, indicated at 19c, upon the face portion 19b of the preheated plastic article 19a, after removal of the die 15 and therewith of the residue of the stamping medium 19, an element of the impressed stamping being indicated by the reference character 19'. Fig. 4, and also Fig. 3, indicate at 19d, 19d, etc., ridges resulting from the aforesaid stamping operation during the stage of and continuing after the stage of the stamping operation, the elements 19' constituting the sight of the impressed stamping and the ridges 19d in similitude of framing about the impressed stamping elements 19'.

Stated generally, the preheating of an article of any given plastic composition is carried to a range of temperature within which the surface portions of its mass attains the characteristic of local cold flow under the pressure of the stamp-

ing press and within which range of temperature the mass of the plastic article loses the characteristic of brittleness under the stamping pressure and also maintains in substantial permanency its physical dimensional characteristics. Fortunately, the plastic compositions in current general use, enumerated in the hereinabove appearing list, attain the above referred to facial displacement and mass non-brittleness and permanency of dimension characteristics within the approximate range from 130° F. upwardly, the upper limit being usually less than 250° F. The results of our discovery indicate, by reason of the local cold flow characteristic imparted to the surface portions of the plastic article, preheated as above set out, that thereby the inner mass of the plastic article, having a definitely lower temperature, is protected from fracture.

Predicated upon the results of our discovery, the temperature to which the die is heated, i. e., by its individual heating element, may, and preferably, approximates closely the minimum temperature of the stated range of preheated temperature of the plastic.

Specifically, plastic articles of phenol-formaldehyde compounds of the type sold under the trade-mark "Bakelite" are commercially satisfactorily stamped pursuant to our invention, as aforesaid, when preheated to a temperature range between 140° F. and 150° F.

Under optimum temperature conditions of the preheated plastic article and of the heated die, as based upon the results of our discoveries, the pressure of the impression, i. e., exerted by the stamping press, may be somewhat less than that pursuant to conventional practice in the use of the particular stamping medium employed.

For the purpose of simplicity and clarity of terminology, we have employed the term "thermo-stampable" plastic as defining any plastic comprised in the above appearing list and possessing the characteristics of being moldable at temperatures from approximately 225° F. upwardly, under compression molding pressure of from 1000 pounds per square inch and upwardly, possessing the attribute of substantially no tendency to cold flow, i. e., at atmospheric temperatures under conventional stamping pressure, and having the characteristic of brittleness at atmospheric temperatures.

Whereas we have described our invention by reference to specific forms thereof, it will be understood that many changes and modifications may be made without departing from the spirit of the invention.

We claim:

1. The method of stamping with metallic foil an article of thermo-stampable plastic which is brittle at atmospheric temperatures under pressure of stamping with a heated die, said method comprising heating such article to a temperature at which a facial portion of such article is locally displaceable under stamping pressure while the mass of the article maintains its dimensional characteristics and is protected from tendency of brittleness under stamping pressure, providing a die bearing on its face the desired metallic configurated impression, providing a heat releasable metallic foil strip embodying a carrier strip bearing on its face a layer of heat releasable bonding medium upon which is applied metallic foil bearing on its exterior face a bonding medium, heating the die face, passing such heat releasable metallic foil strip in contact with the heated die face, and bringing the die and the thus interposed

metallic foil strip in pressure contact with the plastic article while the latter is in its stated heated status.

2. The method of stamping with metallic foil a molded article of thermo-stampable plastic which is brittle at atmospheric temperatures under pressure of stamping with a heated die and is moldable under compression of from 1000 pounds per square inch and upwardly under temperature of from 225° F. upwardly, which comprises heating such article to a temperature at which the facial portion of such article is locally displaceable under stamping pressure while the mass of the article maintains its dimensional characteristics and is protected from tendency of brittleness under stamping pressure, providing a die bearing on its face the desired metallic configurated impression, providing a heat releasable metallic foil strip embodying a carrier strip bearing on its face a layer of heat releasable bonding medium upon which is applied metallic foil bearing on its exterior face a bonding medium, heating the die face, passing such heat releasable metallic foil strip in contact with the heated die face, and bringing the die and the thus interposed metallic foil strip in pressure contact with the plastic article while the latter is in its stated heated status, the stamping pressure being definitely less than the stated compression molding pressure of the plastic.

3. The method of stamping with metallic foil a molded article of thermo-stampable plastic which is brittle at atmospheric temperatures under pressure of stamping with a heated die and is moldable under compression of from 1000 pounds per square inch and upwardly under temperature of from 225° F. upwardly, which comprises heating such article to a temperature definitely less than its stated molding temperature and under a pressure definitely less than its stated molding pressure to render its facial portion locally displaceable under stamping pressure while the mass of the article maintains its dimensional characteristics and is protected from tendency of brittleness under stamping pressure, providing a die bearing on its face the desired metallic configurated impression, providing a heat releasable metallic foil strip embodying a carrier strip bearing on its face a layer of heat releasable bonding medium upon which is applied metallic foil bearing on its exterior face a bonding medium, heating the die face, passing such heat releasable metallic foil strip in contact with the heated die face, and bringing the die and the thus interposed metallic foil strip in pressure contact with the plastic article while the latter is in its stated heated status.
